(57) **CLAIM**

The ornamental design for a display screen with animated graphical user interface, as shown and described.

DESCRIPTION

FIG. 1 is a first view of a new design for a display screen with an animated graphical user interface;

FIG. 2 is a second view thereof;

FIG. 3 is a third view thereof;

FIG. 4 is a fourth view thereof;

FIG. 5 is a fifth view thereof;

FIG. 6 is a first view of the display screen with an animated graphical user interface shown in a different environment;

FIG. 7 is a second view thereof;

FIG. 8 is a third view thereof;

FIG. 9 is a fourth view thereof; and,

FIG. 10 is a fifth view thereof.

The appearance of the animated graphical user interface sequentially transitions between FIGS. 1-5 in one environment, and between FIGS. 6-10 in another environment, respectively. The process period in which one image transitions to another forms no part of the claimed design. The broken lines show portions of the display screen with animated graphical user interface that form no part of the claimed design.
